RELAY

Laurence S. Harrison, Binghamton, N. Y., assignor to International Business Machines Corporation, New York, N. Y., a corporation of New York

Application April 19, 1935, Serial No. 17,246

7 Claims. (Cl. 175—320)

This invention relates to electrically controlled mechanisms and more particularly to a relay which is responsive only to currents of certain frequency characteristics. The invention still more specifically relates to relays responsive to certain frequency characteristics of the vibrating reed type by means of which reeds tuned to vibrate in resonance with certain frequencies operate to close or open contacts or both for the purpose of selectively controlling circuits.

It is the object of this invention to provide a relay having two circuit controlling contacts each controlled by frequency responding members adapted to be responsive at different frequencies.

Another object of this invention is to provide a relay having a reset mechanism for restoring the relay contacts to normal position after having been moved out of normal position by actuation of the relay.

Still another object is to provide a relay having two tuned reeds surrounded by a single coil, each reed being responsive to a different frequency of current passing through said coil.

A still further object is to provide a relay in which tuned reeds are responsive to different current frequencies transmitted to said relay and in which each reed supports an arm of a contact which is tripped to actuate said contact upon vibration of the reed corresponding to said contact.

A still further object is to provide a relay having contacts in which the contact arms are tripped from their normal positions by actuation of reeds adapted to vibrate at certain current frequencies and in which said contact arms are restored to their normal positions by a magnet actuated restoring mechanism.

Various other objects and advantages of my invention will be obvious from the following particular description of one form of mechanism embodying the invention or from an inspection of the accompanying drawings, and the invention also constitutes certain new and novel features of the construction and combination of parts hereinafter set forth and claimed.

In the drawings:

Fig. 1 is a plan view of the relay.

Fig. 2 is a front elevation of the relay.

Fig. 3 is a section on line 3—3 of Fig. 2.

Fig. 4 is a wiring diagram of a circuit including the relay.

Fig. 5 is a detailed section of part of the relay.

Referring to Fig. 1 the relay may be provided with a base 6 of suitable material on which a

bracket 7 is mounted which supports a square shaped magnet yoke 8, the upper horizontal side of which terminates in pole faces 9 leaving a small air gap 10 (Fig. 3). The lower horizontal side 11 of the yoke has integral with it a boss 12 which has an extension 13 on one side to which reeds 14 and 15 are anchored. The extensions 13 act as a stiffener and are of different lengths selected to anchor the reeds in such a way that each has a different but definite period of vibration.

Thus the reed that is supported lowest down with the short stiffener will have a slower period of vibration than the reed which has the stiffener extended higher along the reed. In the present embodiment it will be supposed that these reeds are to vibrate, one in response to currents of 1800 cycle frequency and the other in response to currents of 1200 cycle frequency when such currents are transmitted through the main coil 16

which surrounds one of the vertical sides of the yoke 8. A biasing coil 17 surrounds the reeds. This coil is constantly energized by a current of lower frequency, i. e., 60 cycles and normally holds the reeds in a vertical position so that the ends are held steady substantially in the center of the air gap 10 between the pole faces (Fig. 3).

The bracket 11 is formed upwardly at one end and to this end are mounted two groups of contact springs insulated from each other and terminating in contacts 18 and 19 for one group and 21 and 22 for the other group. The center contact springs have contact arms 23 and 24 extending at right angles to the contact springs.

These contact arms each extend across the plane of one of the reeds so that there is one contact arm corresponding to and associating with each tuned reed. Fixed to the end of each contact arm is a rigid depending member 25 which rests on the end of the reed directly under it as viewed in Fig. 3 so that both contact arms are thus normally supported by its corresponding reed and such a position contact 18 and 21 are normally closed.

It will be seen that if either one or both reeds are vibrated, they will be displaced from under the depending member 25, allowing the contact arm corresponding to or supported by, the reed which is vibrated, to drop and in so dropping will open the normally closed contacts and close the contacts opposite thereto.

For example, if tuned reed 15 vibrates, contact arm 24 will drop from its own weight and contacts 21 will open and contacts 23 will close. It will be seen that if, after the vibrating period of the reed has ceased, the contact arm 24 is raised

50

75

so that the end of the depending member 25 is raised above the end of its corresponding reed, the reed will assume its normal position so that when the contact arm is lowered the depending member 25 will again rest on the end of reed 15 and the contacts 20 and 21 will be restored to their normal or original position.

To accomplish this restoration a reset mechanism is provided. A bracket 26 is mounted on the base 6 and on this bracket is mounted a magnet 27 and a cylinder 28 of an air dash pot. The magnet coil is enclosed in a metal cylindrical jacket and cooperates with a solenoid plunger 29 extending into the core of the magnet winding. The plunger 29 is pivotally fastened to an arm 30 which is in turn pivotally mounted at 31 to an extension 32 fixed to the metal jacket of the magnet coil.

The opposite end of the arm 30 is pivotally connected to a link 33 which is in turn pivotally fastened to an arm 34. The arm is pivotally mounted at 35 to the bracket 26, (Fig. 2). The arm 34 is biased in a clockwise direction by means of a spring 36 fastened between its upper end and a stud 37 on the bracket 26. The lower end of the arm 34 is bifurcated and engages a pin 38 in the end of the piston 39 which is slidably mounted within the air dash pot cylinder 28. An arm 40 is pivotally mounted at 41 to the bracket 26 and is slightly biased in a clockwise direction by a spring 42 which is fastened to said arm at one end and to arm 30 at the other end.

A projection 43 on the arm 40 is formed over to cross into the plane of a pawl 44 which is pivoted at 45 on the bracket 26 and is biased in a clockwise direction by the spring 46 fastened to said pawl and to a stud 47 on the bracket member which also acts as a limit stop for the movement of the arm 40 in a counterclockwise direction since the extension of said arm abuts said stud.

The pawl 44 is provided with a shoulder 49 which latches on the formed-over portion 43 of the arm 40 and prevents said arm turning in a clockwise direction unless unlatched. Pivoted to the arm 40 is a link 50 which is pivoted at its other end to a U-shaped member 51 which is pivoted on the stud 37 mounted on the bracket 26 so that the legs of the U-shaped arm straddle the bracket. The other arm 52 of said U-shaped member carries a stud 53 of suitable insulating material which extends under the contact arms 23 and 24 (Fig. 1). Thus if this U-shaped member is turned in a clockwise direction, the stud 53 will lift both contact arms 23 and 24.

A stud 54 is provided on the arm 30 and cooperates with a downwardly inclined tail piece 55 on the pawl 44 so that a movement of the arm 30 to the right will cause the stud to hit the tail piece and cam the pawl 44 in a counter-clockwise direction to remove the shoulder 49 from its latching position against the formed out portion 43 to permit the arm 40 to rotate in a clockwise direction.

The operation of the reset mechanism is as follows: Assuming one of the reeds have been vibrated to permit one of their associated contacts to function. The reset magnet coil 27 will become energized in a manner later to be explained in connection with the circuits. This magnet will then draw its solenoid plunger into its coil rotating the arm 30 clockwise about its pivot. This rotation will be retarded in its speed by the action of the dash pot as the arm 30 pushes the arm 34 counterclockwise about its pivot through

the link 33, and thus pushes the piston into the air chamber. As the arm 30 moves counterclockwise it increases the tension in the spring 42 fastened to arm 40 since said arm is latched against rotation by the pawl 44 as previously described. As the arm 30 approaches its limit of travel in a clockwise direction, the stud 54 cams the pawl 44 out of latching position, as previously explained, and the arm 40 is moved in a counterclockwise direction by the increased tension in the spring 42, and by means of the link 50 rotates the arm 51 of the U-shaped member in a clockwise direction to lift the contact arms to a height sufficient to permit the reeds to be restored to a supporting position for said contact 15 arms.

When the restoring magnet is deenergized the spring 36 rotates arm 34 clockwise and pushes the link 33 to the left as viewed in Fig. 2. The pivot stud 57 is provided with an extension which extends into the plane of the link 50 and said link is provided with a shoulder 56. As the link 33 is moved to the left the extension of said pivot stud 55 bears against the shoulder 56 and causes the arm 44 to be moved counterclockwise, this movement continuing until the extension 48 strikes the limit stud 47 by which time the arm 40 has moved far enough for the shoulder 49 of pawl 44 to latch up behind the formed-over portion 43 of the arm 40.

Turning now to the wiring diagram shown in Fig. 4 to show the functioning of the relay. It will be understood that the closing of contacts 18 or 20 could be used to control relays or other equipment which could be placed in parallel with the reset coil 27. It is the purpose here however to describe and explain how the relay itself operates and not what it may control by its operation. Let it be assumed now that we have a regular 110 volt 60 cycle commercial current source of supply being transmitted over lines 60 and 61 and that said current is operating a motor 62 which is connected by means of a shaft 63 to two high frequency generators 64 and 65, generating currents of 1800 and 1200 cycle frequency respectively. Blocking condensers 66, 67, 68 and 69, are provided in the circuit to prevent the flowing back of the 60 cycle frequency current or any other stray frequency other than for what that circuit is tuned for. Switches 70 and 71 are provided in the generator circuits and may be automatically operated by time controlled means or by cyclically operated cams, or numerous other well known methods, or they may be operated manually, depending on the use to which the relay may be put. It will be noted that the biasing coil 17 is constantly energized, being connected across the 60 cycle lines 60 and 61 by means of wires 72 and 73, with a resistance 17a in series with said coil.

It will be further noted that one side of each generator is common and grounded at 14. Now let it be assumed that the switch 71 is closed for one second and opened again. When said switch is closed a circuit is completed from one side of the 1200 cycle generator 65 through the condenser 67, switch 71, wires 75 and 76, contact 19 (normally closed) condenser 69, main coil 16, to ground 17 and thence to ground connection 14, wire 78 to the generator. The energization of the main coil 16 by the 1200 cycle current will cause the reed 14 tuned to that frequency to vibrate and cause contacts 18 to close and contacts 19 to open. The opening of contacts 19 will immediately open the circuit to the main

coil and the closing of contacts 18 will now close a circuit from line 60 of the 60 cycle power line, through wires 79, 80, 75 and 76, contacts 18 (now closed), reset magnet 27, wire 73 to the other side of the supply line 61. The reset magnet then operates to reset the contacts as previously described, closing contacts 19 and opening contacts 18. As previously stated, any suitable work or control circuit, can be taken from the reset magnet circuit such as shown by the dotted line circuit 81.

In a similar manner if the switch 70 is closed a circuit is established from one side of the 1800 cycle generator 64 through condenser 66, switch 15 70, wires 80, 75 and 82, contacts 21, condenser 68, main coil 16, ground connection 77 to ground connection 74 and back to the generator 64. The reed 15 tuned to respond to this frequency will 20 vibrate causing contacts 21 to open and contacts 20 to close, again establishing a circuit through the reset magnet 27 from supply line 60 through wires 79, 80, 75 and 82, contacts 20 (now closed) wire 83, reset magnet 27, wire 73 to supply line 61. The energization of the reset magnet will 25 again cause the contacts 20 and 21 to be reset to their normal position as previously explained.

While the fundamental and novel features of the invention as applied to a single modification have been shown and described and pointed out, it will be understood that various omissions and 30 substitutions and changes in the form and details of the device illustrated and in its operation may be made by those skilled in the art without departing from the spirit of the invention. I intend to be limited therefore only as indicated by the scope of the following claims.

What is claimed is as follows:

1. An electromagnetic device including frequency responding members, means including magnetic means for vibrating said members at a certain frequency, normally opened contacts controlled by said frequency responsive members and operable by the vibration of said members, into a closed position, electromagnetic means for restoring said closed contacts to open position and a circuit extending from said contacts to said electromagnetic means whereby the closure of the contacts causes the electromagnetic means to become operable to restore said contacts from closed to open position.

2. An electromagnetic device including a resonant reed having a certain resonant frequency, means including electromagnetic means for vibrating said reed at resonant frequency, a circuit controller controlled by said reed and operable by the vibration of said reed for movement into operative position, electromagnetic means for restoring said circuit controller to inoperative position, a circuit extending from said circuit controller to said electromagnetic restoring means and another circuit extending from said circuit controller to said electromagnetic vibrating means whereby the movement of said circuit controller into operative position renders the electromagnetic vibrating means ineffective and the electromagnetic restoring means effective.

3. An electromagnetic device including a resonant reed having a certain frequency of vibration, means including electromagnetic means for vibrating said reed at resonant frequency, a circuit controller comprising a normally open contact and normally closed contact, means controlled by said reed for normally holding the last named contact in closed position, said last-named

means being operable by the vibration of said reed at its resonant frequency for causing the normally open contact to be closed and the normally closed contact to be opened, and a circuit included in the first named means extending from said normally closed contact to said electromagnetic vibrating means whereby the opening of said normally closed contact terminates the vibration of said reed by the electromagnetic means.

4. An electromagnetic device including a resonant reed having a certain frequency of vibration, means including electromagnetic means for vibrating said reed at resonant frequency, a circuit controller comprising a normally open contact and a normally closed contact, means normally latched in position by said last named reed to hold said contact in closed position, said last-named means being unlatched by the vibration of said reed at its resonant frequency to cause the normally open contact to be closed and the normally closed contact to be opened, electromagnetic means for restoring said contacts to normal position, and a circuit included in the first named means extending from said normally open contact to said electromagnetic means whereby the closing of said normally opened contact renders the electromagnetic restoring means effective to restore said contacts to open position.

5. An electromagnetic device including a resonant reed having a certain frequency of vibration, means including electromagnetic means for vibrating said reed at resonant frequency, a circuit controller normally held in one position controlled by said reed and operable by the vibration of said reed for movement into an alternate position, a restoring device for restoring said circuit controller to its normal position, said restoring device including an electromagnet connected to a circuit extending from restoring device and operable upon movement of the circuit controller to its alternate position, an armature operated thereby, a speed retarding device, and a member controlled by the conjoint operation of said speed retarding device and said armature, whereby the operation of said electromagnet causes said member to move the circuit controller to its normal first named position.

6. An electromagnetic device including a plurality of resonant reeds each having a different frequency of vibration, electromagnetic means for vibrating each reed at its resonant frequency, said means including an electromagnet for receiving electrical current impulses of different frequencies whereby the reeds are severally vibrated in response to current impulses received by said electromagnet of frequencies corresponding to the frequency of vibration of said reeds, a plurality of circuit controllers normally held in a certain position each controlled by a different reed and operable by the vibration of its controlling reed for moving the circuit controller controlled by said vibrating reed into an alternate position, a restoring device for restoring all circuit breakers to their normal certain positions, said restoring device including an electromagnet connected to circuits extending to each of said circuit controllers and operable upon movement of any one of said circuit controllers to its alternate position and means operated by said electromagnet upon energization thereof for restoring said circuit controllers to their normal first named certain position.

7. An electromagnetic device including a resonant reed having a certain frequency of vibration, electromagnetic means for vibrating said reed at resonant frequency, a switching member controlled by said reed and movable from normal position to an alternative position by the vibration of said reed, means for restoring said

switching member to said normal position, and means controlled by said switching member for causing the latter when moved to its alternate position to render the electromagnetic means inoperative and to render the restoring means 5 operative.

LAURENCE S. HARRISON.
